(57) **CLAIM**

The ornamental design for a lighter, as shown and described.

DESCRIPTION

FIG. 1 is a top, front perspective view of a lighter, showing my new design;

FIG. 2 is a bottom, rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion 9 in FIG. 1; and, FIG. 10 is an enlarged view of the portion 10 in FIG. 7.

The evenly dashed broken lines illustrate portions of the lighter and form no part of the claimed design. The unevenly dashed broken lines surrounding details shown in FIGS. 1, 7, 9 and 10 are for purposes of annotating the enlarged views only and form no part of the claimed design.

1 Claim, 10 Drawing Sheets
